Inventor

UNITED STATES PATENT OFFICE.

ALBERT L. ANDREWS, OF WYMORE, NEBRASKA.

DEVICE FOR PULLING BOLTS AND PIPES.

1,254,961.

Specification of Letters Patent. Patented Jan. 29, 1918.

Application filed May 23, 1916. Serial No. 99,431.

To all whom it may concern:

Be it known that I, ALBERT L. ANDREWS, a citizen of the United States, residing at Wymore, in the county of Gage and State of Nebraska, have invented certain new and useful Improvements in Devices for Pulling Bolts and Pipes; and I do hereby declare the following to be a full, clear, and exact description of the invention, such as will enable others skilled in the art to which it appertains to make and use the same.

The invention relates to a device for pulling bolts, pipes and the like.

The object of the present invention is to improve the construction of lifting jacks and to provide a simple, practical and comparatively inexpensive device designed for pulling bolts, pipes and the like and capable of easy operation and of exerting great force in pulling a bolt or extracting a pipe from a well or the like and adapted also to securely grip the object operated on so that there will be no liability of the bolt, pipe or the like slipping.

With these and other objects in view, the invention consists in the construction and novel combination of parts hereinafter fully described, illustrated in the accompanying drawing, and pointed out in the claims here appended; it being understood that various changes in the form, proportion, size and minor details of construction, within the scope of the claims, may be resorted to without departing from the spirit or sacrificing any of the advantages of the invention.

In the drawings

Figure 1 is a central vertical sectional view of a bolt pulling device constructed in accordance with this invention,

Fig. 2 is a rear elevation of the same,

Fig. 3 is a horizontal sectional view of the bolt pulling device,

Fig. 4 is a detail perspective view of the lower portion of the vertically movable lifting bar,

Fig. 5 is a detail sectional view illustrating the manner of mounting the adjustable jaw and the opposite wedges,

Fig. 6 is a detail perspective view of the adjustable jaw.

Like numerals of reference designate corresponding parts in the several figures of the drawings.

In the accompanying drawings in which is illustrated the preferred embodiment of

the invention, the bolt and pipe pulling device comprises in its construction, a frame or support 1 consisting of a base 2, opposite sides 3 and a rear supporting portion 4. 60 The base is provided with an opening or slot 5 for the reception of an arm 6 extending from the lower portion of a vertically movable lifting bar 7 which is guided in suitable ways 7^a located at opposite sides of 65 the frame or support and preferably formed by cleats 8 but any other suitable form of grooves or ways may of course be employed as will be readily understood. The vertically movable lifting bar which is provided 70 at its rear face with ratchet 9 has the arm 6 extending forwardly from its lower end and it is adapted to be raised by being alternately engaged by a pair of pawls or dogs 10 and 11. The pawls or dogs 10 and 75 11 which are arranged at an inclination are pivoted at their lower ends at 12 and 13 to an operating lever 14 at the inner and outer sides of the pivot or fulcrum point 15 of the same and the said operating lever is pivoted 80 adjacent to its inner end between projecting ears or lugs 17 of the rear supporting portion 4 of the frame or support 1. The rear supporting portion 4 of the frame or support 1 is provided at its upper end with a 85 recess 16 in which the inner arm or portion of the lever 14 operates as clearly illustrated in Fig. 1 of the drawings. The operating lever is adapted to be swung upwardly and downwardly and the pawls or dogs 10 and 90 11 are caused to alternately engage and lift the vertically movable bar or member when the said lever is oscillated and the said pawls or dogs will also operate to maintain the bar or member 7 in its vertical adjustment. 95

The arm 6 which extends horizontally from the lifting bar or member 7 is provided with a substantially rectangular opening 18 and it has a fixed jaw 19 located at the inner end of the opening and coöperating with an adjustable jaw 20 which is movable toward and from the fixed jaw 19. The jaws are provided at their engaging faces with horizontal teeth or serrations to enable them to securely grip a pipe, rod or 105 other object operated on and the adjustable jaw is preferably provided with a rounded engaging face 21 and it has upper and lower horizontally projecting lugs 22 located at the upper and lower faces of the 110 horizontal arm 6 and slidably connecting the adjustable jaw with the same. The ad-

justable jaw which is adapted to engage a pipe or rod at the outer face of the same is adjusted by means of a horizontally disposed screw 23 piercing the outer portion 5 of the arm 6 centrally of the same and in order to relieve the screw the arm is equipped with a pair of wedges 24 located at opposite sides of the screw and adapted to cause the adjustable jaw to grip the bolt, 10 pipe, rod or the like and they obviate any liability of the threads of the screw being stripped therefrom during the operation of the device. The frame or support is designed to be equipped at opposite sides with 15 chains 26 having terminal hooks 27 to enable the frame or support to be mounted upon a rail or secured in any position for operating on bolts or the like. When the jaws are engaged with a bolt, pipe, rod or 20 the like, the lever is adapted to be operated to move the lifting bar or member upwardly or outwardly and it will be clear that pipes, rods and the like will be successively moved upward or outward with comparative ease. 25 The lever 14 may be equipped in its outer end with a socket 29 to enable a handle 30 of any desired length to be employed for operating the device.

What is claimed is:—

30 1. A device of the class described including a frame having spaced guides, a lifting bar slidable in the guides and provided with a projecting arm having an opening, said arm being also provided at the inner end of 35 the opening with a relatively fixed jaw, a horizontally adjustable jaw slidably mounted in the opening at the outer portion thereof for inward and outward adjustment and

coöperating with the fixed jaw, a centrally arranged adjusting screw mounted on the 40 said arm and arranged to move the adjustable jaw inwardly and a pair of wedges located in the opening of the said arm at opposite sides of the screw and movable upwardly and downwardly independently 45 of the adjustable jaw and adapted to relieve the screw of strain.

2. A device of the class described including a frame, a vertically movable lifting bar guided in the frame and provided at 50 the lower portion with an arm having an opening, said lifting bar being also provided at the inner end of the opening with a relatively fixed jaw, a horizontally adjustable jaw operating in and extending through 55 the opening of the said arm and provided above and below the same with lugs arranged in pairs and slidably interlocking the adjustable jaw with the arm and preventing vertical movement when the adjustable jaw is in its normal engaging position and permitting the removal of the adjustable jaw from the opening when the 60 said adjustable jaw is turned out of such position, an adjusting screw mounted in the outer end of the arm and engaging the adjustable jaw for moving the same inwardly, and an independently movable wedge interposed between the adjustable jaw and the 65 outer end wall of the said opening.

In testimony whereof I affix my signature in presence of two witnesses.

ALBERT L. ANDREWS.
